UNITED STATES PATENT OFFICE.

ERNEST NIEHOFF, OF BROOKLYN, NEW YORK.

VALVE ATTACHMENT FOR TORPEDOES.

No. 820,888.

Specification of Letters Patent.

Patented May 15, 1906.

Application filed May 9, 1904. Serial No. 207,142.

To all whom it may concern:

Be it known that I, ERNEST NIEHOFF, a citizen of the United States, residing at Brooklyn, New York, have invented certain new and useful Improvements in Valve Attachments for Torpedoes; and I do hereby declare the following to be a full, clear, and exact description of the invention, such as will enable others skilled in the art to which it applies to make and use the same.

This invention relates to improvements in explosive projectiles, and particularly to torpedoes; and the object of the invention is to provide a suitable means for controlling the depth of the torpedo and the sinking of the same at the proper time, together with means for causing the explosion of the projectile after a suitable interval.

The invention also comprises an explosive projectile and means for causing the explosion thereof under the action of the pressure of the water in which the projectile is moving.

The invention further comprises a travelling projectile, means for floating the same a suitable length of time, and means for causing the explosion of the torpedo comprising a valve mechanism and a firing member controlled thereby, the said valve being affected by the pressure of the water in which the torpedo floats.

It also comprises certain other novel constructions, combinations, and arrangements of parts, as will be fully described and claimed.

In the accompanying drawings, Figure 1 is a side elevation of a torpedo constructed in accordance with the present invention. Fig. 2 is an enlarged detail sectional view through the central portion of the valve mechanism and the firing-pin controlled thereby. Fig. 3 is a longitudinal sectional view through the buoyant member of the torpedo with the valve and shield for controlling the inlet of water for sinking the torpedo. Fig. 4 is a bottom plan view of the said buoyant member, showing the exterior of the valve-shield.

The present invention is designed for providing a torpedo with a simple means for floating and controlling the sinking thereof, the said mechanism being also capable of causing the explosion of the torpedo in accordance with the pressure of the water in which the torpedo is sunk.

In the drawings I have illustrated a practical means of carrying out the features of this invention.

In the drawings, 1 represents a torpedo, 2 a buoyant member, and 3 a valve member. The torpedo may be made in any desired form and is preferably provided with a suitably-operated propeller 4 or other means by which it may be driven through the water. The torpedo 1 is suspended from the buoyant member 2 by suitable hangers or standards 5. The pressure of the water in which the torpedo travels plays an important part in the operation of the device, and therefore the buoyant member is so constructed that the torpedo will be floated for a predetermined space of time and then be permitted to sink, the pressure of the water when at the proper depth operating to cause the explosion of the projectile.

The construction of the float is quite simple. It preferably consists in a hollow closure either of a cylindrical or other shape and closed at the ends. In the bottom of the float 2 is an opening guarded by an inwardly-projecting tube 6. This tube is formed with a valve-seat upon its inner end, and a valve, 7, is pivoted to the tube and engages the said valve-seat normally for preventing the passage of water through the tube. The casing of the float also carries a shield, as 8, the shield consisting of an elongated metal piece preferably tapered from one end toward the other, as shown in Fig. 4. The closed narrower end of the shield is adjacent to the tube 6, while the wide flaring open end of the shield is arranged at a suitable distance from the tube. The shield 8 forms a very shallow chamber between it and the lower wall of the buoyant member, so that when the torpedo is launched into the water the water will be retarded in its endeavor to enter the buoyant member. This retardation of the water is increased by the movement of the torpedo, the closed end of the shield 8 being toward the front of the torpedo, while the open end is at the rear. A small aperture 9 is formed in the buoyant casing 2 near the top thereof, so that as the water finally forces its way between the shield and the walls of the buoyant member and lifts the valve 7 the air contained in the buoyant member will have a means of escape, and the water can thus gradually fill the buoyant member, causing the gradual sinking of the torpedo at the proper time. As the torpedo sinks in the water the pressure of the water will of course increase in proportion to the depth attained, and when the torpedo has been lowered in

the water a sufficient distance the pressure will reach a sufficient strength to operate the torpedo-exploding mechanism.

The means for producing the explosion of the torpedo consists principally in a pressure-actuated valve and a firing-pin carried by the member 3. This member consists in a hollow sectional casing which is preferably located in a vertical position in the upper part of the torpedo 1.

The position of the valve mechanism with respect to the torpedo is indicated in dotted lines in Fig. 1. The casing of the valve member 3 is preferably made in two sections 10 and 11. The section 11 is formed with external threads 12, by which it may be screwed into position in the threaded aperture formed in the torpedo-casing 1. Inside the casing-section 10 is mounted a sliding valve 13, which is hollow for the greater portion of its length and receives a coiled spring engaging the valve, while the other end rests against the floor or partition 15, formed near one end of the casing-section 10. Mounted in this casing-section also are a plurality of spring-arms or grippers 16. These spring-arms are secured to the casing-section 10 near one end thereof, and their free ends project through apertures formed in the partition 15 at their other ends and extending a short distance beyond the casing-section 10. The end of the section 10 which is adjacent to the section 11 is reduced in size and threaded, the said reduced end engaging a threaded annular socket 17, formed in the adjacent end of the section 11. The section 11 is made hollow, the bore thereof extending through it from end to end. Mounted in the bore of this section is a firing-pin 18, which is preferably hollow and is formed with an annular recess 19 upon its inner end, which is engaged by the inturned gripping ends of the spring-arms 16. When the firing-pin 18 is forced into the casing a sufficient distance to engage the said spring-arms, a spring 20, which is inserted within the firing-pin 18, will be considerably compressed, as shown in Fig. 2, and its strength is such that when the firing-pin is released it will force the same outwardly with considerable power. The outer end of the casing 10, which is arranged flush with the outer surface of the torpedo, is closed by means of a cap or plug 21. The said plug is provided with a series of perforations or passage-ways 22, which pass through it, admitting exterior pressure to the interior of the casing-section 10.

The operation of the mechanism is somewhat as follows: When the torpedo is launched, its propelling mechanism of course is set in motion, and the buoyant member 2 will float the torpedo for a considerable length of time. While the torpedo is thus held near the surface of the water, the pressure thereof will not be sufficient to overcome the strength

of the spring 14. After a suitable length of time has elapsed the gradual filling of the buoyant member 2 with water will cause the whole structure to gradually descend in the water. The pressure of the water as it enters the passages 22 and engages the end of the valve 13 will increase with the depth of the water, and when the pressure is sufficient to force the valve inwardly in the casing-section 10 the said valve will spread the inner ends of the spring gripping-arms 16, and thus release the firing-pin 18. A percussion-cap or other suitable explosive agent is so placed within the torpedo as to be struck by the firing-pin when it is forced out of the casing 11 by means of the compressed spring 20. It will be thus seen that the explosion of the torpedo is made dependent on the degree of pressure exerted upon valve 13. It will also be seen that the degree of pressure exerted upon said valve is controlled automatically by the floating and sinking of the torpedo through the action of the buoyant member, together with its valve and shield, as above described.

The construction of the parts forming the novel features of this invention is exceedingly simple, and the apparatus is automatic in its action and dependent upon the pressure exerted by the water in which the torpedo is launched.

It will be evident that the details of construction may be varied without departing from the spirit of the invention.

I contemplate employing the valve mechanism above described in connection with any kind of a marine projectile, for when such a valve is applied to any shell of any kind if the shell falls short of its mark and drops into the water it will not be lost, for when it reaches a given depth the valve mechanism will cause its explosion.

Having now described the nature of my said invention, what I claim as new, and desire to secure by Letters Patent, is—

1. A firing device comprising a casing, firing means arranged therein, a spring governing the operation of said firing means, and means adapted to be wedged into engagement with said spring for effecting a release of the firing means for permitting operation thereof.

2. In a device of the class described, the combination with an explosive projectile, and means for temporarily maintaining said projectile buoyant, and for permitting sinking at the conclusion of the temporary buoyancy, of means for exploding said projectile, and means adapted to be operated by the pressure of the surrounding water for controlling the operation of said exploding means.

3. A firing device comprising a firing-pin, means for throwing the same into a firing position, a laterally-movable spring arranged at

one side of said firing-pin, a hook carried by said spring normally engaging said pin for retaining the same against operation, and pressure-governed means for releasing said 5 spring.

4. A firing device comprising a casing, a firing-pin longitudinally movable therein, a spring arranged longitudinally within said casing, means for throwing said pin, means 10 carried by said spring normally engaging said pin for preventing the throwing thereof, and pressure-governed means for moving said spring laterally for releasing said pin.

5. A firing device comprising a casing, a firing-pin arranged therein, means for throwing said firing-pin to a firing position, an annular groove being formed in said pin, springs arranged longitudinally of said casing and formed with hooks normally extending into 15 said groove, and pressure-operated means for pressing said springs for removing the hooks from the groove.

6. A firing device comprising a casing, a firing-pin arranged within, means for throwing 20 said pin for producing a firing operation thereof, springs arranged longitudinally of said casing and engaging said pin for preventing such firing operation, said springs being bent intermediate their length, and 25 pressure-operated means adapted to be pressed between said springs in contact with said bent portions for throwing said springs out of engagement with said pin.

7. The combination with a container for 30 explosive materials, of a casing extending into the same, a firing-pin arranged within said casing, means for locking said pin against operation, a valve mounted to slide longitudinally of said casing, a spring normally pre-

venting such movement of said slide, means 40 engaged by said slide when moved longitudinally for releasing said pin, and means for throwing said pin for accomplishing an igniting operation thereof when the pin is released.

8. A firing device comprising a casing, firing means arranged therein, springs governing the operation of said firing means, and a valve adapted to be wedged between said springs when subject to pressure for releasing 45 said firing means.

9. A firing device comprising a casing, firing means arranged therein, a spring extending longitudinally of said casing, and acting laterally for retaining said firing means out of operation, and means designed to be 50 moved by pressure into engagement with said spring for moving the same laterally to a position for releasing said firing means.

10. An explosive projectile comprising a firing member, gripping means engaging the 55 same from opposite sides, and a valve member capable of spreading the gripping means when submitted to a given pressure.

11. A firing device comprising a casing, firing means arranged therein, springs extending longitudinally of said casing, and acting laterally for retaining said firing means out of operation, and pressure-governed means adapted to be moved longitudinally of the springs between the same for 60 spreading the same apart and releasing said 65 firing means.

In testimony whereof I hereunto affix my signature in presence of two witnesses.

ERNEST NIEHOFF.
